UNITED STATES PATENT OFFICE

THOMAS B. BENNETT, OF MUSKEGON, MICHIGAN, ASSIGNOR TO BENNETT PUMPS CORPORATION, OF MUSKEGON, MICHIGAN, A CORPORATION OF MICHIGAN

PNEUMATIC GREASE PUMP

Application filed March 15, 1926. Serial No. 94,674.

This invention relates to an air operated grease dispensing pump. It is desirable in the dispensing of grease to supply a high pressure grease gun as it is called, with a continuous supply of grease from a relatively large reservoir or container of grease. The grease which is supplied to the high pressure gun is supplied continuously and under relatively low pressure but sufficient 5 that it will force the grease that is needed into the high pressure gun.

In the present invention it is designed that a relatively large container of grease may be equipped with an air operated grease pumping outfit which may be readily operated by compressed air so as to continuously dispense grease under sufficient pressure that it will continuously supply the high pressure gun with the desired and necessary amount 10 of grease or dispense the grease to any other desired place.

The invention consists in many novel details of construction and arrangements of parts for attaining this end, as well as many others not at this time particularly enumerated in an efficient and practical manner, as will appear when understanding of the invention is had from the following description taken in connection with the accompanying drawings, in which,

Fig. 1 is a vertical section through the grease dispensing outfit of my invention.

Fig. 2 is an enlarged horizontal section through the control valve associated therewith.

Fig. 3 is a fragmentary enlarged view similar to Fig. 1 showing a different form of the construction wherein the pumping piston is operated in both directions by compressed air, and

Fig. 4 is an enlarged horizontal section through the air control valve used with the form of the invention shown in Fig. 3.

Like reference characters refer to like parts in the different figures in the drawings.

The main supply of grease is contained within a receptacle or other container 1, which is preferably of sheet metal, having 50 a bottom 2 the upper end being closed by

a top 3. This top is provided with an opening which is normally covered by plate 4 detachably secured in place by the thumb screws 5 shown.

A vertical pump barrel 6 is located within the container 1 and at its lower end is seated in a seat formed at the upper end of a casting 7 which tapers downwardly and inwardly for a distance. The upper end of the barrel is received in a seat formed in the under side of a member 8 bolted or otherwise suitably secured permanently to the plate 4, which plate has a circular opening for the upper end of barrel 6. The cylinder is secured in place in the usual and well known manner by rods which extend through the members 7 and 8. These rods are not shown in the drawing but the lower nuts 9 attached to the ends of the rods are shown below the upwardly extending flange 70 at the upper end of the member 7.

The member 7 at its lower portion is extended downwardly making a cylindrical projection 10 interiorly threaded for the reception of the upper threaded end of a short pipe 11 which extends downwardly to the bottom 2 of receptacle 1. The lower end of pipe 11 is cut at an angle, indicated at 12, for providing a wide entrance for grease from the receptacle into the lower end to 80 pipe 11.

A web 13 having vertical openings through it is cast integral with and extends across member 7 at the upper end of part 10. A valve plate 14 lies above this web and 85 normally closes the openings when in lower position. A pin 15 extends from the center of the valve plate downwardly through the web and a cotter pin is passed through the lower end of pin 15 so that the vertical 90 movement of the valve plate is limited upwardly by the engagement of the cotter pin against the under side of web 13.

The plate 8 at the upper end of cylinder 6 is formed for the mounting of a suitable 95 stuffing box 16 through which a vertical piston rod 17 passes. The lower end of the rod is equipped with a piston 18 which has vertical openings through it normally covered and closed by a movable valve plate 19 slid-

ably mounted on rod 17 and lying against the upper side of the piston 18 when in its lower position. A pin 20 passes through the rod 17 a distance above the valve plate 19 limiting the upward movement of the plate 5 as is evident.

The upper member 8 previously described is formed with an outlet neck 21 one side of which is continued outwardly in an extension 22 to which any suitable flexible hose connection may be attached, at its outer end having the high pressure grease gun secured thereto in the usual manner. The outlet neck 21 is formed with openings 22^a in opposite sides which when they are not used may be closed by suitable screw plugs but which, if it is desired to have more than one line of hose run from the apparatus, may be removed and replaced by a suitable connection having a hose attachment which connection can thread into opening 22^a.

Above the member 8 a supporting standard 23 is located and it is secured in place by the same rods and nuts used to bind the barrel 6 and the member 7 and 8 together. This casting has a horizontal web 24 across it between its upper and lower ends, the rod 17 passing through the web and through the usual form of stuffing box 25 which prevents 30 the escape of air around the piston rod from above the web 24 as will later appear.

A cylinder 26 is located above and its lower edge is received in a suitable seat formed in the upper end of the standard 23. The upper end of the cylinder is closed by an upper head 27 and this head and the barrel are secured to the standard 23 by rods 28 which pass through the flanges on the head 27, and on the standard 23.

The upper end of the piston rod 17 terminates within the cylinder 26 and a somewhat larger rod 29 is attached to its upper end and extends through the head 27 being equipped at its upper outer end with a knob 30. A valveless piston 31 is located within the cylinder 26 and secured to the rod 29. The piston 31 is of conventional construction having an outer cup leather associated therewith, which will not permit the escape 50 of air upwardly past the piston.

Compressed air is carried through an inlet pipe 32 to a valve casing 33 and therefrom through a short pipe connection 34 into the standard 23, any air passing therein going into the cylinder 26 below the piston 31. The valve 35 mounted within the casing 33 is designed to be turned about a vertical axis by handle 36. Valve 35 has a horizontal passage 37 through it and also a lateral smaller branch passage 38 from the passage 37 to the outer side of the valve. And the casing 33 is provided with a vent opening 39 in one side.

In the operation of this construction, 65 valve 35 is turned from the position shown

in Fig. 2 so that the passage 38 aligns with the pipe 34 and the passage 37 at one end joins with the vent opening 39. The knob 30 may then be operated so as to push the piston rod downwardly any air under the piston 31 passing outwardly through the vent opening 39, while with the downward movement of the piston 18, grease flows upwardly therethrough elevating the valve plate 19. The valve 35 may then be turned to position shown in Fig. 2. This will open the passage from air inlet pipe 32 to the cylinder 26 and compressed air flowing into the cylinder and under the piston 31 will tend to elevate said piston and the rods connected therewith, forcing the grease above piston 18 outwardly through the neck 21 and the hose attached to the outlet 22. The pressure of the compressed air need not be high to accomplish this. As the grease is dispensed from the high pressure gun attached to the hose, piston 18 is elevated more and more and thus keeps the high pressure gun continuously supplied. Of course, this greasing outfit is quite as useful for dispensing grease through a hose outlet whether or not a high pressure grease gun is attached at its end and, in many instances, it will be used merely as a dispensing outfit for conveying grease from the container 1 to a transmission or differential gearing casing in an automobile or to any other place where a lubrication is desired without the interposition of a high pressure grease gun; and with more than one outlet to the neck 21, both the high pressure grease gun attachment and the regular measured quantity grease dispensing hose may be used. In any event the grease is dispensed outwardly with the upper movement of the piston 18 which goes upwardly under the force of air pressure against piston 30 as the grease passes out through the neck 21.

With the upward movement of the piston 18 valve plate 19 drops to its lower position shown in Fig. 1 and the grease above the piston cannot return through the piston downwardly, but grease from the container will pass upwardly through the pipe 11, elevating the valve plate 14 and passing by it so that the barrel 6 is filled below the piston 18 as said piston moves upwardly; and on the down stroke of the piston 18 valve plate 14 moves to lower closing position shown in Fig. 1 and the grease below the piston 18 passes upwardly through it and by the valve plate 19 as previously described.

Instead of operating the rod 17 and the attached pistons downwardly by hand as described with reference to the construction shown in Fig. 1, the operation of the rod 17 in both directions may be effected by air pressure. The construction for accomplishing this is shown in Fig. 3 wherein the cylinder 26 is provided with a somewhat dif-

ferent form of head plate 27^a having an inlet portion 40 as shown. The rod 29 and the knob 30 are eliminated and the piston 31^a is secured at the upper end of the rod 17. Pipe sections 34^b and 34^a are threaded into the inlet member 40 and through the standard 23, at both the upper and lower ends of the cylinder 26. The compressed air is carried through an inlet pipe 41 to a 10 valve casing 33^a which has upwardly and downwardly extending pipes 42 connected therewith, the same being connected at their upper and lower ends respectively with the pipe sections 34^b and 34^a previously noted. 15 The valve 43 in casing 33^a is of a form such that by turning it to one position, as shown by Fig. 4, air may pass from the pipe 41 through the pipe 42 to above the piston 31^a while the air below the piston will be vented 20 outwardly through the lower pipe 42 and the vent opening 39; and when the valve is turned to another position this passage of the air will be reversed, the compressed air going into the cylinder below the piston 31^a. 25 and the air above piston venting outwardly through vent opening 39. The upward and downward movements of the grease dispensing piston 18 in this manner are both controlled by compressed air instead of the upward movement alone as shown in the construction illustrated in Fig. 1; otherwise the 30 operation of the two forms of the apparatus are identical.

This construction of grease dispensing apparatus is very practical and effective and is of particular value in garages where the dispensing of grease for lubricating automobiles is common. The apparatus is readily operated by compressed air, is easily 35 controlled and the grease can be dispensed to where it is used very conveniently and expeditiously without the necessity of the one handling the apparatus coming into contact with the grease in any manner. The 40 invention is defined in the appended claims and all forms of structure coming within the scope of said claims are to be considered as comprehensive of the invention.

I claim:

50 1. In a construction of the class described, a container for grease having an upper end with an opening therein, a grease pump adapted to be inserted through said opening in the end of the container and located in 55 said container, comprising a grease pump cylinder, a lower cylinder head with an inlet valve and means communicating with said inlet valve and extending near the bottom of the container, a piston in the grease 60 pump cylinder, a passage through said piston, a check valve in said passage, an upper cylinder head having a grease outlet above the head of the container, a plate connected with said upper cylinder head covering said 65 opening in the end of the container and sup-

porting the structure, a piston rod attached to said piston and extending through said upper piston head and pneumatic means located above the upper piston head and connected with said piston rod for reciprocating said rod and piston. 70

2. In a construction of the class described, a container for grease having an upper end with an opening therein, a cylinder and piston type grease pump adapted to be inserted through said opening in the head of the container and located within the same, a plate attached to said grease pump at its upper end, said plate covering the opening in the head of the container and supporting the pump structure, a piston type pneumatic pump located above the oil pump and outside of the container and supported by said plate, means connecting the pneumatic pump and the oil pump whereby the pneumatic pump serves to actuate the oil pump and a grease outlet from the upper end of the oil pump cylinder outside of the container. 75 80 85

In testimony whereof I affix my signature. 90
